UNITED STATES PATENT OFFICE.

IGNATIUS J. VETTER, OF NEW YORK, N. Y.

PHONOGRAPH.

Application filed September 11, 1923. Serial No. 662,031.

My invention relates to phonographs or sound reproducing apparatus and, generally stated, its object generally is to increase the volume and quality of the tone and at the same time secure faithful reproduction of the recorded sound.

More specifically the object of my invention is to reproduce or impart natural tone to recorded or transmitted sounds and to amplify, modify, separate and balance the tones of different instruments and voices and also to eliminate all objectionable and mechanical noises.

By my invention it becomes possible to dispense with the horn ordinarily employed and to cause the sounds to be reproduced wholly by sound boards and resonators.

To these ends, my invention consists essentially in delivering the sounds from the tone arm into a space or enclosure, one or more bounding walls of which consist of a freely vibrating sounding board, the enclosure into which the sound is so delivered being completed by other suitable sound confining boards some or all of which may be freely vibrating sound boards free to vibrate at their edges as hereinafter described. In some cases, said sound confining boards which complete the enclosure may have the function only of confining the sound and not be themselves the source of sound vibrations but, in such case, they must be so applied to complete the enclosure as not to interfere with the free vibration of the sound boards which respond to the sound within the enclosure and serve directly or in conjunction with other devices to reproduce the tones or vibrations.

My invention consists also in a phonograph cabinet or enclosure and in details of construction of sound amplifying devices and resonators and in the arrangement of the same, as hereinafter more particularly described and then specified in the claims.

In the accompanying drawings, I have shown my invention as embodied in or carried out in connection with apparatus having features of construction and characteristic devices that are described and claimed in my prior Patent No. 1,487,299, dated March 18, 1924.

My invention is however useful in connection with reproducing apparatus of other forms as will be apparent from the subjoined description taken in connection with the accompanying drawings, in which

Fig. 1 is a vertical, central section through the apparatus in its preferred form.

Fig. 2 is a perspective view of the bank of amplifying boards used in the space or enclosure connected directly to the tone arm or outlet thereof through which the sounds reproduced by the stylus are delivered.

Fig. 3 illustrates in perspective one of said boards with the preferred shape of end thereof where it bears against a sounding board or bridge therefor.

Fig. 4 is a perspective view of the top of the apparatus with a part shown in section and other part broken away.

Fig. 5 is a perspective view of the resonator forming the enclosing bottom of the stand or cabinet.

Fig. 6 is a perspective view of a board or wall suitable for use in completing the enclosure, one side or wall of which consists of the freely vibrating sound board responsive to the sounds delivered from the tone arm into the enclosure.

Fig. 7 is a perspective view of a portion of the bank or rack of sound boards forming a sound vibrational carrier and amplifier between the freely vibrating sound board forming a wall of the enclosure into which the sounds are directly delivered from the tone arm and a vertical resonator arranged within the reproducer cabinet.

Fig. 8 is a rear view of the part shown in Fig. 6.

Fig. 9 shows the preferred form of one of the vertically disposed resonators.

Fig. 10 shows the manner of applying the compression clip or bar thereto.

Fig. 11 is a perspective view of the sound boards or resonators upon which the rack of sound boards within the sound receiving enclosure is engaged at its end.

Fig. 12 shows in perspective parts of the framing at the bottom of the cabinet whereby the resonators of Fig. 11 are supported.

1 indicates the base of the cabinet or enclosure for the apparatus hereinafter de-

scribed and 2 the sides rising therefrom and consisting preferably of panels perforated or cut out in fret work of any desired design backed up by silk or any light weight fabric 5 2' that will permit the sound to pass through. These panels may be set in separate frames so that they can be easily removed.

Within the cabinet or enclosure of the apparatus and near the top thereof is mounted 10 the table or board 3 sustaining the record turntable 4, driving motor therefor in casting 5, and the sound conductor or tone arm 6 to which is connected the outlet or passageway 7 through which the sounds are delivered from the tone arm to the amplifier. 15

The various sound boards of which the apparatus is composed, as hereinafter described, are preferably made of wood having good resonant quality such as seasoned 20 spruce board, or may be made of other resonant material. The side walls of a space or enclosure into which the sounds reproduced by the stylus are delivered from the outlet 7 of the tone arm are indicated at 8. 25 Two such walls forming opposite walls of said enclosure are shown. Said walls 8 consist of sounding boards which are unconfined at their edges and are free to vibrate over their whole surface. The enclosure is completed by other walls 8' applied and 30 constructed so as not to interfere with the vibration of the edges of the walls 8, as will be presently described. The walls 8 may be supported from the bottom side of the table 35 3, as shown, by being bolted thereto. These side walls 8 are engaged in sound conducting relation through racks or banks of sound transmitting and amplifying boards 9 with the sides of vertically disposed resonators 10 40 in a manner to be presently described. Between them and in line with the outlet 7 is a bank or rack of sound boards, such as indicated in Fig. 2, vibratively engaged and connected by their surfaces with the surfaces 45 of the boards 8 by sound posts or dowels 11 which are glued or directly secured in firm engagement with the various boards so as to form a solid medium for transmitting sound between them. The rack or bank of 50 boards may be sustained within the enclosure of which the sound boards 8 form a wall and extend downwardly from the outlet 7 and preferably into proximity to a sound reflector 12, which may be of concave 55 form as shown, to reflect the sounds upwardly and outwardly, and the boards of the sound amplifying rack are of graduated or different lengths, as indicated, for the purpose of supplying boards for readily responding to sounds or tones of different rates 60 and said boards at one end, as for instance their upper end, are cut away or reduced as to the amount of material in them to assist in their ready vibration. Said amplifying 65 rack is sustained at its lower end in vibrative

connection, by its edge, with sounding boards forming the boards of a resonator or resonators 13 by making one or more of the boards of the rack extend through an opening in the reflector 12, as shown, and into 70 engagement with a bridge or bridges 14 which rest upon the upper surface of the horizontally disposed resonators 13. As shown, the central board 11' of the amplifying rack is used for this purpose, said central board being connected in sound vibrative relation, through sound posts, with the remaining members of the rack or bank at opposite sides thereof. Preferably, the end of the board 11' is cut into an arch, as indicated in Fig. 3, to form a bridge, the abutments of the bridge being preferably beveled or sharpened to engage the notches 14' 75 in the resonator bridges 14, thereby holding the board 11' in position and insuring solid, 80 vibrational connection thereof with the bridges. 85

It will be seen that the sound posts of the rack or bank do not extend through all of the member boards of the amplifier but merely connect the same in pairs and that the posts of successive pairs are in staggered relation which, I find in practice, is an advantageous relation for this member of the apparatus so far as concerns volume and capacity for vibrating the different tones or rates of tones and for the effective transmission of the vibrations of one board to the others and to the sound boards 8 forming the walls of the sound receiving enclosure 95 already referred to. This same staggered relation of sound posts or dowels between successive pairs of sound boards is adopted also for the vibrational carriers and amplifiers 9 which are employed in a manner similar to the amplifiers described in my prior application filed May 29, 1922, Serial No. 564,645, for transmitting the sound vibrations from the sides 8 of the amplifier to the sides of the resonators 10. 100

Also, as will be seen, the edges of the sound boards for the banks 9 are cut away or tapered to assist in the production of sound effects therefrom. The sound posts connecting the sides 8 with the racks 9 are indicated at 15 and the sound posts connecting the racks or banks 9 with the sides of the resonators are indicated at 16. All the parts are compressed and kept under tension by cross rods 17 which connect bearing clips or bars 18 bearing against the outside corners of the resonators 10, as shown in Fig. 10 compression being applied by means of the thumb nuts 19, as described in my prior application. 115

The resonator 10 at the left is sustained in vertical position by posts, as shown, engaging the top of a table or support 20 in the base and the bottom of the table 3, while the resonator 10 at the right is supported in 120 125 130

a similar way in upright position, excepting that its upper supporting post engages the bottom of the casing for the motor 5.

To secure the best effects from the transmission of the vibrations endwise from the amplifying rack within the space bounded by the wall 8, I prefer to employ two resonators or sets of sounding boards 13 arranged in crossed relation as shown in Fig. 11, and 10 to apply to each a bridge 14 in such way that it will be sustained at its opposite ends respectively by the members forming the pair of resonators 13. Each said resonator may consist of a pair of sounding 15 boards connected by sound posts, as indicated, so that it will be open at its edge but its ends are closed by solid blocks of wood 22, as shown in Fig. 11, which receive supporting bolts 23, the latter passing through 20 openings in the diagonal bases or blocks 24 at the corners of the framing at the bottom of the cabinet or enclosure, as illustrated in Fig. 12.

The top of the cabinet is closed in by 25 a resonator one board of which, forming the upper board of the resonator and indicated at 25, covers the entire area of the top. Said board 25 may have scroll or F-openings or holes F cut out in position 30 shown in Fig. 4 to improve the acoustic effects or reproductions given out by said top resonator. The lower sound board of this resonator, indicated at 26, is approximately only one-half the size of the upper 35 board 25, although I do not limit myself to this proportion of size. It is suitably secured at its edges in the side wall of the cover. A sound post is forced between these boards to keep them in tension and the lower board 26 is preferably formed with 40 an opening 26' which, in conjunction with the scroll openings, permits the air to circulate between and around the boards and prevents sound reflections.

45 As will be seen, the two boards form in effect a resonator with one end open. Opposite the open end, one or more sound boards 27 are disposed and suitably supported in the sides of the cover. These 50 boards are preferably arranged so that the plane of each board will form an angle with the plane of the sound boards of the resonator. One of them extends partially into the space between said boards 25 and 26 and, for the best effects, the plane of each 55 board 27 forms an angle with that of the other. The edges of the boards preferably taper to a point or are reduced at their lower ends and do not touch at any other point excepting that where they are supported in the sides of the cover. These 60 boards respond to the vibrations set up in the top resonator and act to further amplify said sounds and improve the quality by 65 responding to different rates of vibration,

said boards being, as shown, of different area.

The object of the arrangement described is to utilize and amplify the musical sounds in the top of the machine and in amplifying said musical sounds the objectionable mechanical sounds are practically masked or eliminated.

The bottom of the cabinet is closed by a resonator, the two boards of which are indicated at 28 while 29 shows the sound posts connecting them. Said resonator is properly supported firmly in the base and is preferably provided with the oval openings 32 cut out as illustrated in Figs. 1 and 5 and 70 with the F or scroll openings F¹, as indicated in Fig. 5, these openings being for the same purpose as those provided in the resonator forming the top of the cabinet. The sounding boards of the resonator 28 may be kept 75 under tension by one or more sound posts 33 interposed between the upper board 28 and the resonator 13 as shown in Figs. 1 and 11.

In practice, I utilize only the two side walls 8 for transference of the vibrations 90 to the vertically disposed resonators, in which case the remaining two walls 8' may be constructed as indicated in Fig. 6. Said walls 8' close the space between the two side walls 8 to complete the enclosure connected with the tone arm and each wall 8' may be provided with the dowels at its upper end and with a flange at its lower end for holding the same in place. Each wall is also provided with flanges or extensions 30, 100 31 extending at right angles from the plane thereof, the flange 30 lapping upon the outer side of the sides 8 and the flange 31 entering in the space between the side 8 and the outer member of the bank of boards forming the 105 amplifier. As will be seen, the flanges provide a groove which receives the free edge of the vibratory side 8. The edges of the flange 31 are shown notched to afford space 110 for the sound posts 11 in the amplifier bank. The purpose of this construction is to form a good closure at the corners where the sides 8 and 8' meet without interfering with the free vibrations of the sides 8.

What I claim as my invention is:— 115

1. In a sound reproducing apparatus of the character described, an amplifying device consisting of a bank of sound boards in sound vibrative connection with one another and disposed substantially in alignment with 120 the direction of movement of the sound waves therein, said sound boards being of graduated length or area.

2. In a sound reproducing apparatus, an amplifier consisting of a bank of sound boards disposed substantially in alignment with the direction of movement of sound therein and secured in vibrative connection in pairs by posts positioned in staggered 125 relation between successive boards. 130

3. In a sound reproducing apparatus, an amplifier consisting of a bank of sound boards secured in sound vibrative connection with one another, said boards having the outer free edges thereof terminating in reduced ends.
4. In a sound reproducing apparatus, the combination with an amplifier consisting of a bank of sound boards, of a sounding board and a bridge bearing against said sounding board and supporting an edge of a board of said bank.
5. In a sound reproducing apparatus, the combination with a source of sound waves, of an amplifier board disposed in line with the direction of movement of the sound waves emanating from said source, and a resonator operatively engaged with said board through an edge thereof.
6. The combination with a rack of sound boards, of a pair of resonators arranged in crossed relation, and bridges whose ends are supported respectively upon said resonators, said bridges being connected in sound vibrative engagement with a board of said rack.
7. In a sound reproducing apparatus, the combination with a source of sound waves, of an amplifier for receiving said sound waves, said amplifier including a sound board, and an additional sound transmitter and amplifier comprising a bank of sound boards having free reduced edges and secured in sound vibrative connection with said first-named sound board.
8. In a sound reproducing apparatus, a sound amplifier, an enclosure for said apparatus, said enclosure embodying a plurality of resonators in the outer walls thereof for augmenting the effect of said amplifier.
9. In a sound reproducing apparatus, a source of sound waves, an amplifier for receiving and transmitting said waves, an enclosure for said apparatus, said enclosure including an outer wall and an inner wall spaced therefrom and a sound post connecting said walls.
10. In a device of the class described including a source of sound waves, an amplifier disposed in the path of the sound waves emanating from said source, of a concave sound reflector positioned adjacent the outlet from said amplifier and means mounted in vibrative connection with said amplifier for conducting the sounds therefrom.
11. In a sound transmitting device, an amplifier comprising a rack of sound boards for receiving and amplifying sounds, a sound reflector positioned adjacent an end of said amplifier, a resonator, means connecting said amplifier and resonator in sound vibrative connection, said means extending through said reflector.
12. In a sound reproducing apparatus, an amplifier for receiving sounds, means in vibrative engagement with said amplifier for conducting sounds outwardly therefrom, an enclosure for said apparatus, and additional means, forming a portion of said enclosure, for receiving and transmitting sounds from within said enclosure.
13. In a sound reproducing apparatus, an amplifier comprising a bank of sound boards having the edges thereof free to vibrate, and closing sides for said edges mounted adjacent to said edges but free from contact with said boards.
14. In a sound reproducing apparatus, an amplifier including a plurality of sound boards, one of said sound boards having its edges free to vibrate and forming an outer wall of said amplifier.
15. In a sound reproducing apparatus, an amplifier including a plurality of sound boards, one of said sound boards having its edges free to vibrate and forming an outer wall of said amplifier, a resonator, and means for conducting sounds from said sound board to said resonator.
16. In a sound reproducing apparatus, a source of sound waves, an amplifier in the path of the waves emanating from said source, and a resonator comprising a main sounding board and a plurality of other sounding boards spaced from said main sounding board, certain of said other sounding boards being arranged at an angle to said main sounding board.

Signed at New York in the county of New York and State of New York this 8th day of September A. D. 1923.

IGNATIUS J. VETTER.
